UNITED STATES PATENT OFFICE.

RAUL MARTEL, OF FALL RIVER, MASSACHUSETTS.

LOOM-BRAKE.

1,098,278.

Specification of Letters Patent.

Patented May 26, 1914.

Application filed November 29, 1911. Serial No. 663,611.

To all whom it may concern:

Be it known that I, RAUL MARTEL, a citizen of the United States, residing at Fall River, in the county of Bristol and State of Massachusetts, have invented new and useful Improvements in Loom-Brakes, of which the following is a specification.

This invention appertains to looms and more particularly to the controlling means whereby the mechanism is started and stopped. In the general construction of looms the drive belt is shifted by means of an operating lever and when it is required to stop the loom a brake shoe is applied to a brake wheel, the brake mechanism being brought into operation the instant the loom is thrown out of action by the shifting of the drive belt from the tight to the loose pulley.

This invention provides means for automatically releasing the brake after the same has been applied to stop the loom so that when the operating lever is actuated to start the loom the latter may respond quickly because of its freedom from the brake which has been previously released.

The invention contemplates an attachment which is applied to the operating lever to automatically release the brake after the loom has come to a standstill, the attachment being of simple nature and effective in operation so as to insure a release of the brake at the proper time, namely when the loom has come to rest.

The invention consists of the novel features, details of construction and combination of parts, which hereinafter will be more particularly set forth, illustrated in the accompanying drawing, and pointed out in the appended claim.

Referring to the drawings, forming a part of the specification, Figure 1 is a detail view in elevation of the frame of a loom, showing the drive pulley and brake wheel together with the operating lever and concomitant parts. Fig. 2 is a detail view of the operating lever and parts carried thereby, showing the relative position of the brake lever and operating parts when the loom is running. Fig. 3 is a view of the parts illustrated in Fig. 2, showing their relation when the loom is stopped.

Corresponding and like parts are referred to in the following description, and indicated in all the views of the drawings, by the same reference characters.

The numeral 1 designates the frame of the

loom, which may be of any construction. The operating lever is indicated at 2 and may be arranged in any convenient position so as to throw the loom into or out of action. 60 The main shaft 3 is provided with a brake wheel 4 and pulleys 5, the latter comprising the usual tight and loose pulleys which cooperate with a drive belt 6. Suitable connections are interposed between the operating lever 2 and drive belt 6 for shifting the latter from the tight pulley to the loose pulley and vice versa. A brake shoe 7 is arranged to engage the brake wheel 4 and is mounted upon one end of a lever 8, the opposite end of said lever being connected to the brake lever 9. The brake lever 8 is fulcrumed between its ends, at 13, and is rigidly connected at its lower end to the lever 9, which latter forms in effect a continuation of the lever 8 so as to move therewith. The combined weight of the lever and the lower portion of the lever 8 is greater than the weight of the brake shoe and the upper part of the lever 8, hence when the outer 80 end of the lever 9 is unsupported the brake shoe is held in engagement with the brake wheel.

An arm 10 is clipped or otherwise adjustably connected to the operating lever 2 and has an inclined portion forming a cam which engages the brake lever 9 so as to hold the brake shoe 7 away from the brake wheel 4. When the operating lever 2 is actuated to throw the loom out of action 90 the brake lever 9 rides downwardly upon the inclined or cam portion of the arm 10 to admit of the brake shoe automatically coming into play so as to stop the loom.

The releaser 11 is pivotally connected to 95 the cam arm 10 and its lower end is weighted so as to normally hold the releaser in approximately vertical position. The releaser consists of a bar 11 pivoted between its ends to the arm 10 and having a stepped 100 portion 12 above and near the pivot connection between the said bar and arm, the lower end of said bar being heavy to normally hold the bar in vertical position. When the loom is running the outer end of 105 the brake lever 9 engages and rests upon the upper outer end of the arm 10, thereby holding the brake out of action. Upon moving the upper end of the lever 2 inward to throw the drive belt from the tight to the 110 loose pulley, as when it is required to throw the loom out of action, the arm 10 is with-

drawn from engagement with the lever 9, thereby permitting the brake to come into play to quickly check the motion of the loom. During this movement of the lever 2 the 5 lever 9 will engage a step of the part 12 of the bar 11 and cause the latter to incline to the vertical—Fig. 3. To start the loom the upper end of lever 2 is drawn outward to throw the drive belt from the loose to the 10 tight pulley and at the same time the bar 11 is moved and tending to assume a vertical position lifts the outer end of the lever 9 and releases the brake. When the arm 10 engages the lever 9 the part 11 is released 15 and swings into vertical position. The lever 9 is bolted or otherwise rigidly connected to the lower outer end of the lever 8 and the combined weight of the lever 9 and the lower half of the lever 8 is greater than the weight 20 of the brake shoe 7 and the upper half of the lever 8 so that when the outer end of the lever 9 is unsupported the brake shoe is pressed against the brake wheel. When the loom is running the outer end of the 25 lever 9 is supported by means of the arm 10. The lever 2 is operated quickly when throwing the loom out of action. Upon operating the lever 2 to shift the drive belt from the tight to the loose pulley the inclined portion 30 of the arm 10 is withdrawn from beneath the outer end of the lever 9, thereby permitting the brake shoe to come into play. When the brake shoe engages the brake wheel the latter is instantly stopped because the rotation of the brake wheel is such as to cause a jamming of the brake shoe thereagainst. During the complete movement of the operating lever 2 there is a period when the 35 outer end of the lever 9 is clear of the arm 10 and the releaser 11 and during this period the brake shoe comes into play to bring the loom to rest. The operation of the brake 40

shoe is momentary, it being the object of the invention to stop the loom instantly so as to prevent any overthrow of the shuttle or 45 other working parts after the power has been disconnected by the shifting of the drive belt.

From the foregoing description, taken in connection with the accompanying drawing, 50 the advantages of the construction and of the method of operation will be readily apparent to those skilled in the art to which the invention appertains, and while I have described the principle of operation of the 55 invention, together with the device which I now consider to be the best embodiment thereof, I desire to have it understood that the device shown is merely illustrative, and that such changes may be made when desired as are within the scope of the claim ap- 60 pended hereto.

Having thus described the invention what is claimed as new, is:—

In a loom the combination of a brake 65 wheel, a brake shoe, a brake lever, an operating lever for throwing the loom into or out of action, an arm attached to and movable with the operating lever and having a cam portion to engage with the brake 70 lever and hold the brake out of action when the loom is running, and a bar pivoted between its ends to the said arm and having its lower end weighted to cause the bar to normally assume a vertical position and 75 having a stepped portion above and near the pivot connection between the said bar and arm.

In testimony whereof I affix my signature in presence of two witnesses.

RAUL MARTEL.
